CLAIM

The ornamental design for a toy truck, as shown and described.

DESCRIPTION

FIG. 1 is a front, right, and top perspective view of a toy truck, showing my new design;

FIG. 2 is a rear, left, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a detailed view of the encircled portion "9" in FIG. 1;

FIG. 10 is a detailed view of the encircled portion "10" in FIG. 2;

FIG. 11 is a perspective view thereof when it is opened; and, FIG. 12 is another perspective view thereof when it is opened.

The dot-dash broken lines in FIGS. 1, 2, 9, and 10 denote the boundaries of the detailed areas and form no part of the claimed design. The even dash broken lines in the drawings are portions of the toy truck that form no part of the claimed design.
